UNITED STATES PATENT OFFICE.

JAMES MACPHAIL, OF BLUE ISLAND, ILLINOIS.

DESIGN FOR A SHELF-SUPPORTING BRACKET.

SPECIFICATION forming part of Design No. 24,490, dated July 16, 1895.

Application filed May 17, 1895. Serial No. 549,703. Term of patent 14 years.

To all whom it may concern:

Be it known that I, JAMES MACPHAIL, a citizen of the United States, residing at Blue Island, in the county of Cook and State of Illinois, have invented and produced a new and original Design for Shelf-Supporting Brackets, of which the following is a specification, reference being had to the accompanying drawings, forming a part thereof.

10 In the drawings, Figure 1 is an isometrical view of my shelf-supporting bracket. Fig. 2 is a side elevation of the same.

The leading features of my design consist

of a horizontal sole A, a vertical wall-plate B, and an upwardly-curved connecting-lug C, 15 projecting outward and upward from the back side of the upper portion of the vertical wall-plate B.

What I claim is—

The design for shelf-supporting brackets, 20 substantially as herein shown and described.

JAMES MACPHAIL.
